UNITED STATES PATENT OFFICE.

GEORGE RICHARD SCHUELER, OF KINGSTON-UPON-HULL, ENGLAND.

CENTRIFUGAL SEPARATOR.

Application filed September 27, 1923. Serial No. 665,080.

To all whom it may concern:

Be it known that I, GEORGE RICHARD SCHUELER, a citizen of the United States of America, residing at the city and county of 5 Kingston-upon-Hull, England, have invented certain new and useful Improvements in Centrifugal Separators, of which the following is a specification.

This invention relates to centrifugal separators.

My invention has for its object, improvements in centrifugal apparatus for separating liquids from solids, whereby the feed of the material from which the liquid is to be separated or extracted and the discharge of the extracted liquid and the residuum or solid matter, take place during the time the apparatus is running and effecting separation, with the result that it is not necessary to stop the apparatus either to charge it or to remove the separated liquid and solids; feeding of the material to be treated, separation or extraction of the liquid from the solid matter, and discharging of 25 the separated liquid and solids proceeding as a continuous operation so long as the apparatus is running.

In carrying out my invention, I employ a vertical cylindrical metal casing, the top and bottom of which are preferably removable.

Rotatable in this casing is a perpendicular shaft on which is keyed or otherwise secured a strong circular plate of a suitable 35 diameter, and rotatably mounted on such perpendicular shaft is a sleeve provided with a fixed circular device disposed a suitable distance above the circular plate on the perpendicular shaft and adapted to cover 40 the same, the outer part or edge of this circular device being of arch or like shape to form an arch or like shaped annular chamber in the top of which are a number of holes, the periphery or edge of such circular device 45 extending beyond the periphery of the circular plate and being provided with a depending flange or rim between the inside of which and the periphery of the circular plate on the perpendicular shaft is a 50 suitable annular space.

The top or upper surface of the device on the sleeve is provided with an annular space into which the material from which the liquid is to be separated, is fed, holes

being formed in such circular device 55 through which the material fed into the circular space passes into the space between the said device and the top of the circular plate and on to the latter.

A ring, preferably cone-shaped, may be, 60 and is by preference, secured to the bottom of the depending flange or rim of the circular device mounted on the rotatable sleeve, the said ring enclosing a portion of the underside of the disc or circular plate 65 on the perpendicular shaft, and serving to deliver the solid matter from which the liquid has been separated into an annular space in the bottom of the casing, through 70 which annular space it escapes through an outlet or outlets provided for the purpose, a suitably driven sweeper, or a plurality of sweepers travelling around in such annular space, carrying such solid matter to the 75 said outlet or outlets.

The circular plate and the circular device which encloses the top and the periphery of the same, are driven by any suitable means in the same direction but one a little faster than the other.

The casing is provided with an internal annular trough which receives the liquid separated or extracted from the material, which liquid is caused by centrifugal force to be delivered on to the inside of the wall 85 of the casing, down which wall it flows into the said annular trough and escapes through an outlet or outlets therefrom.

The periphery of the plate on the perpendicular shaft may be, and preferably is, 90 provided with a plurality of devices each provided with an inclined or like rib to push the solid matter down the annular space between such periphery and the annular depending flange or rim of the circular device which covers such plate, and the circular plate has attached to its underside a plurality of inclined blades, or a ring provided with a plurality of inclined blades for scraping the inside face of the conical ring 95 to prevent lodgment of solid matter thereon.

Having thus stated the object and described the nature of my invention, I will now proceed to describe my said invention in greater detail, and in so doing will refer to the accompanying four sheets of explanatory drawings on which Fig. 1 is a sectional elevation of a centrifugal separator in accord-

ance with my invention, and Fig. 2 is a plan view of the apparatus. Fig. 3 is a plan view of the circular device carried by the sleeve rotatable on the perpendicular shaft. Fig. 4 is a plan view of the circular plate carried by the perpendicular shaft. Fig. 5 is a broken sectional view of the circular plate carried by the perpendicular shaft, the circular device carried by the sleeve rotatable on the perpendicular shaft, and a portion of one of the devices fitted in the periphery of the circular plate and of the ring provided with a blade or blades secured to the underside of such plate, and Fig. 6 is a plan view of the left hand portion of Fig. 5. Fig. 7 is an elevation of the ring provided with inclined blades, detached from the circular plate. Fig. 8 is an edge view of one of the devices provided with the inclined rib or blade with which the circular plate is provided, and Fig. 9 and Fig. 10 are an end view and a plan view respectively of the same.

Figs. 5 and 6 are drawn to a larger scale than the other views.

Referring to the drawings, A indicates the cylindrical casing, A¹ being the cover plate, and A² the bottom plate both shown secured to the said casing by bolts whereby they are removable.

B is a perpendicular shaft the bottom end of which is seated and rotatable in a socket bearing a in the bottom A² of the casing A, the said shaft passing up through the cover A¹ of the said casing, and C is a circular distributing plate keyed or otherwise suitably secured on such shaft, e being a nut screwed on a threaded portion of the shaft to assist in supporting such plate.

D is a sleeve rotatable on the perpendicular shaft B, and E is a circular separating device keyed or otherwise suitably secured on such sleeve, and prevented from working down the same by the conical bottom end of the sleeve and the boss b on the shaft B, e being an annular trough or space formed in the top of the said device E and into which the material from which the liquid is to be extracted, is fed, and e¹ are passages formed in the device within such space, through which the material passes to the space F between the said device and the circular plate C and so on to such circular plate.

The outer portion of the device E is of arch or like shape as indicated at e² to provide a correspondingly shaped annular chamber in which the separation of the liquid from the solid matter takes place, a large number of small holes e³ being formed in the crown of such chamber, through which holes the separated liquid escapes. The periphery of the arch or like shaped outer part of the circular device extends downwardly to enclose the periphery of the

circular plate C mounted on the perpendicular shaft B, a suitable annular space intervening between the two through which the solid matter from which the liquid has been extracted or separated, escapes.

G is a ring preferably cone-shaped as shown, secured to the bottom of the depending periphery of the circular device E on to the inclined inside face of which the solid matter which passes between the periphery of the circular plate C and the inside of the periphery of the circular device E falls, and down which it slides and falls to the bottom of the casing A.

The bottom edge of the conical ring G extends inwardly of the separating holes e³ so that the said edge is nearer the axis of rotation of the separating device than the said holes. The material in the separating device E is stratified by centrifugal action. The heavier and more solid particles of the material are forced outwardly against the imperforate periphery of the separating device E, and the lighter and more liquid particles are permitted to escape through the separating holes, which are arranged inwardly of the imperforate periphery of the separating device E.

H indicates a ring provided with blades h, h, h preferably of the kind shown, see especially Fig. 7 of the drawings, the said blades forming scrapers the inclined bottoms h¹ of which push down any of the solid matter which may lodge on the inside of the conical ring G and so prevent solid matter accumulating on such ring.

J, J, J indicate three devices with which the circular plate C is shown provided, the said devices being each in the form of a segmental plate provided at its outer edge with an upwardly and downwardly projecting flange or rim j, having an offstanding inclined thickened portion which forms an inclined blade j¹ as shown more clearly in Figs. 8 and 9. These plates are secured to the top of the circular plate C, the periphery of which is recessed at each place where a plate is fitted, the inside face of the downwardly projecting flange or rim of a plate bedding against the bottom or inner part of the recess in the circular plate, in which the plate is fitted, see more especially Fig. 5 of the drawings.

The number of devices J employed may be greater or less than three.

K is a flat ring secured to the circular plate C conveniently by the screws k which secure the segmental plates J, J, J to such plate, which segmental plates support the said ring above the circular plate at a distance therefrom corresponding with the thickness of such plates, the said ring K being of sufficiently large diameter to extend beyond the holes e³ in the crown of the annular chamber of the circular device E, and

providing with the outer part of the circular plate C, a space in which the material fed to the circular device E passes to the outer part of the annular chamber, such ring K preventing the material from rising in the said annular chamber until it reaches the edge of the said ring.

L is an annular trough formed by means of the annular upwardly projecting ring or member L¹ formed on (or it may be secured to) the inside of the wall of the casing, into which trough the liquid extracted or separated from the solid matter and which is delivered on to the inside of the casing, flows, l being an outlet in the wall of the casing and in communication with the trough L, through which outlet the liquid escapes from the trough. A pipe (not shown) is preferably connected to the wall of the casing at the point where the outlet l is situated, to convey the liquid to a store tank.

M is an annular channel or space at the bottom of the casing, formed by an annular ring-like portion M¹ on the inside of the bottom plate of the casing, into which space the solid matter from which the liquid has been extracted or separated falls, m being a spout-like outlet from such annular channel or space, and which is conveniently formed integral with the bottom plate A² of the casing A.

N is a bevel wheel rotatable on an upwardly projecting central boss-like portion O of the circular chamber A³ formed integral with the bottom plate A² of the casing, n, n¹ being bent members secured to the back of such bevel wheel, n², n³ being sweepers secured to the outer ends of the bent members and which travel around in the annular channel or space M formed by the ring-like projection M¹ on the inside of the bottom plate of the casing and sweep the material in such channel to and through the outlet m therefrom.

P is a horizontal shaft rotatable in a bearing p fitted to one side of the chamber A³ combined with the bottom plate A² of the casing A, and in a sleeve p¹ secured to such bearing p, p¹ being a bevel wheel keyed on the inner end of such shaft and which gears with the bevel wheel N which carries the bent members n, n¹ provided with the sweepers n², n³ and causes the rotation of the bevel wheel N and through it, the circular travel of the sweepers n², n³, and P² is a pulley keyed on the outer end of the shaft P, the said pulley being connected by a belt with a pulley on a line of shafting or the like.

R is a circular hopper-shaped device supported by rods r carried by the cover A¹ of the casing A, the said hopper projecting into the annular feed trough or space e in the top of the circular device E, and R¹ is a tube through which the material is fed to such

hopper, the said tube being connected to the bin or the like containing the material to be treated.

S is a pinion or like toothed wheel keyed on the perpendicular shaft B, S¹ is a similar wheel but of a little larger diameter, keyed on the sleeve D rotatable on the shaft B.

T is a perpendicular short shaft, the bottom end of which is seated and rotatable in a socket bearing a¹ on the top of the cover A¹ of the casing A, which shaft passes up through a bearing conveniently formed in a removable plate a² forming the cover of a cylindrical casing or chamber a³ formed on the top of the cover A¹ of the casing A, T¹ being a spur or like toothed wheel keyed on the shaft T and which gears with the pinion or like toothed wheel S on the shaft B, and T² is a slightly smaller spur or like toothed wheel keyed on the said shaft T and which gears with the pinion wheel S¹, keyed on the said sleeve D, the difference in the diameter of the two pinion wheels S, S¹ on the shaft B and on the sleeve D respectively, and the difference in the diameter of the spur wheels T¹, T² on the shaft T, causing the shaft B provided with the circular plate C to be driven at a slightly higher speed than the sleeve D provided with the circular device E.

U is a pulley keyed on the top of the short shaft T and V, V¹ are two jockey pulleys rotatable on a short shaft v carried by an upright v² mounted on a bracket W carried by the side of the casing a³, X being a driving belt connecting the pulley U on the short shaft T with a pulley on a line of shafting or other driving source, which belt passes under the jockey pulleys V, V¹ and drives the shaft T which in turn drives the perpendicular shaft B and the circular plate C thereon and the sleeve D and the circular device E thereon through the medium of the spur wheels T¹ and T² and the pinion wheels S and S¹, the shaft B and the sleeve D being both driven in the same direction but the one at a little higher speed than the other.

The cylinder a³ on the cover plate A¹ of the casing A and the cover plate a² of such cylinder a³, constitute a housing for the pinion wheels S, S¹ and the spur wheels T¹, T². The cover plate a² of the cylinder a³ is conveniently provided with a hollow boss a⁴ provided with a bush a⁵ to form a bearing for the top end of the perpendicular shaft B which is preferably sufficiently long to project through such cover plate a².

The material from which the liquid is to be extracted or separated is fed through the tube R¹ into the hopper R, down which it passes into the annual trough or space e in the top of the circular device E on the sleeve D rotatable on the perpendicular shaft B from which trough or space e it

passes through the holes or passages e^1 and falls on to the circular plate C keyed on the perpendicular shaft, and is caused by the speed at which the circular plate C 5 revolves to pass under the guide ring K and is guided by the said plate C and ring K to a point beyond the points at which the separated liquid and the solid matter from which the liquid has been separated, are 10 discharged from the circular device E, through the separating holes e^3 . The solid matter is separated from the liquid matter in the separating device, and the liquid escapes through the holes e^3 therein and is 15 deposited on the walls of the casing A down which it flows into the annular trough L and escapes through the outlet L.

The solid matter from which the fluid has separated, is engaged by the blades of 20 the devices J fitted in the recesses in the periphery of the circular plate C keyed on the shaft B, and is forced by them down the annular space between the outer wall of the circular device E and the periphery of 25 the circular plate C, whence it falls on to the conical ring G secured to the bottom of the periphery of the circular device E down which it is pushed and caused to descend by the blades h of the ring H attached 30 to the underside of the circular plate C. This solid matter falls into the annular channel M in the bottom plate A² and is swept by the sweepers n^2 , n^3 on the bent arms n , n^1 carried by the bevel wheel N, 35 to the outlet M.

Any liquid which, not having separated 40 from the material in the annular chamber of the device E but may separate therefrom as the material passes down the ring G, may pass back into the space between the plate C and the guide ring K and into the material therein through holes c^1 provided in the plate C for the purpose.

The whole of the operative parts of the 45 apparatus are entirely enclosed, thereby enabling the apparatus to deal with materials or mixtures containing liquid of a volatile nature, such as, for example, oil, fat and the like containing material, to which benzine or other volatile solvent has been added 50 to effect or assist in effecting the extraction of the oil or the like from the material.

What I claim and desire to secure by Letters Patent is:—

55 1. In a centrifugal separator, a rotary distributing plate, a rotary separating device arranged over the distributing plate and provided at its inner portion with a receiving chamber for the material which 60 delivers the material onto the inner portion of the top of the distributing plate, said separating device having also an annular chamber arranged at its outer portion between its receiving chamber and its periphery and 65 provided at its top with separating holes

for liquid and having its bottom formed by the said distributing plate, said separating device having also an imperforate and downwardly projecting peripheral portion spaced apart from the periphery of the distributing plate and forming with it an annular discharge outlet for solid matter, and separate driving devices operating to rotate the said distributing plate and separating device independently of each other. 75

2. A centrifugal separator as set forth in claim 1, the said receiving chamber for the material being annular and provided with a series of downwardly and outwardly inclined passages for delivering the material 80 onto the distributing plate.

3. In a centrifugal separator, a rotary distributing plate, a rotary separating device having an imperforate peripheral portion and an annular separating chamber 85 provided with separating holes for liquid at its top, said holes being arranged inwardly of its imperforate peripheral portion and over the distributing plate, a conical ring secured to the said separating device and projecting inwardly of its separating holes and below the distributing plate, and means for preventing solid matter from accumulating on the said conical ring. 90

4. A centrifugal separator as set forth in 95 claim 3, the said rotary distributing plate being provided with holes extending through it and operating to connect the liquid space inside the conical ring with the liquid space of the annular separating chamber.

5. A centrifugal separator as set forth in claim 3, the said means for preventing solid matter from accumulating on the conical ring, comprising scrapers secured to the 100 said distributing plate. 105

6. A centrifugal separator as set forth in claim 1, the said distributing plate being provided with passages having covered tops in the upper side of its outer part which 110 conduct the material from its inner portion to the peripheral part of its annular chamber past its said separating holes.

7. In a centrifugal separator, a rotary distributing plate, an annular guide plate, segmental plates secured between the top of the distributing plate and the annular guide plate, thereby forming a series of passages which conduct the material from the central portion of the delivery plate to its periphery, and a rotary separating device having 115 an imperforate peripheral portion and an annular separating chamber arranged over the said guide plate and provided with separating holes for liquid. 120

8. In a centrifugal separator, a rotary distributing plate, a rotary separating device having an imperforate peripheral portion and an annular separating chamber provided with separating holes, a conical ring secured to the said separating device and projecting 125 130

below the distributing plate, and a casing for the said parts provided with an annular receiving chamber for solid matter below the said conical plate, said casing having 5 also a ring which projects inwardly and upwardly from its side wall above the said receiving chamber, said ring being arranged

around the said conical ring and forming with the wall of the casing an annular receiving chamber for liquid. 10

In testimony whereof I have affixed my signature.

GEORGE RICHARD SCHUELER.
